GRINDING MILL

Filed March 27, 1944

UNITED STATES PATENT OFFICE

2,405,692

GRINDING MILL

John R. Hall, Chicago, Ill., assignor to International Harvester Company, a corporation of New Jersey

Application March 27, 1944, Serial No. 528,224

1 Claim. (Cl. 241—239)

1

This invention relates to a new and improved grinding mill and has for one of its principal objects the provision of means for automatically releasing the cylinder concave upon entrance of some hard material which would normally tend to break parts of the grinding mill unless the operation of the mill was halted in some way.

An important object of this invention is to provide a feed grinding mill capable of having its concave released from its operative position adjacent the cylinder either manually or automatically.

Another and still further important object is to provide a hinged concave yieldably held in position adjacent a cylinder which is automatically releasable and capable of repositioning by a mere manual swinging of the concave.

Other and further important objects will become apparent from the disclosures in the following specification and accompanying drawing, in which:

Figure 1 is a longitudinal sectional view of the grinding mill of this invention;

Figure 2 is a sectional view taken on the line 2—2 of Figure 1; and

Figure 3 is a sectional view similar to Figure 2 with the concave in released position.

As shown in the drawing, the reference numeral 10 indicates generally a housing for a grinding mill and includes a feed inlet hopper 11 which permits grain or other material to be ground to reach a cylinder 12 which, as shown in Figure 1, has a spiral flighting 13 extending around the periphery and lengthwise of the cylinder. A concave 14 is positioned beneath and closely adjacent the cylinder 12 so that material carried by the spiral flighting 13 is compressed and partially ground against the concave 14. In order to more thoroughly grind material, the inner surface of the concave 14 is roughened as at 15 and shown in all the figures of the drawing.

The concave 14 is hinged above the horizontal center-line of the cylinder 12 at 16 to lugs 17 which form an integral part of a casting 18 bolted or otherwise attached as shown in Figure 2. A cutting blade 21 is bolted to the upwardly extending flanges 18 at 22 and extends inwardly to a point very close to the periphery of the cylinder spiral flighting 13. The cylinder 12 rotates in a counter-clockwise direction as viewed in Figure 2 and indicated by an arrow 23. It will be apparent that as material to be ground is fed longitudinally by the spiral flight-

2

ing 13 it will be positively sheared by the cutting blade 21.

The lower end of the semicylindrical concave 14 is equipped with an outwardly extending radial flange 24, the surface of which is inclined as shown at 25. The flange 24 is adapted to abuttingly engage a member 26 which is rigidly affixed to the hopper walls 11. A release lever 27 is hinged at 28 on rearwardly extending hinge lugs 29 of the member 26. The forward portion of the lever 27 has an inverted V-shaped surface including inclined sides 30 and 31 and an apex 32. The lever 27 has a relatively large opening 33 through which a long bolt 34 is adapted loosely to pass. The bolt 34 extends through the hopper wall 11, through the member 26, and thereupon through the opening 23 in the lever 27. The bolt 34 is retained in its position by means of a head 35 at its upper end and a nut 36 at its lower end. A spring 37 is interposed between the nut 36 and the lever 27, thereby resiliently maintaining the lever 27 in its uppermost position as shown in Figures 2 and 3. The yieldable latch is below the horizontal centerline of the cylinder 25 and on the opposite side from the hinge 16.

In Figure 2 the concave 14 is yieldably locked in an operative position adjacent the cylinder 12. The inclined surface 30 of the lever 27 engages the inclined surface 25 of the concave flange 24. It is possible in feeding grain or other material to a grinding mill to accidentally put in some foreign object such as a rock which would be hidden by the grain and which would tend to cause great damage to the machine parts of a feed grinder unless some safety means was provided. At the present time wooden shear pins are employed to a great extent to prevent such accidents, but this method has proved inconvenient in reassembling the grinding mill in order to resume operation.

The action of the present device is to automatically permit the inclined surfaces 24 and 30 to slide apart relative to each other and thus permit the concave to swing about its hinge 16 and take the position shown in Figure 3. The releasing of the concave is instigated upon overcoming the force of the spring 37. Therefore, when an obstruction enters the cylinder and concave, a downward force is applied to the concave 14 which acts directly on the spring 37 through the lever 27. It is obvious that no parts will be broken, and that the obstruction, whatever it may be, will drop down through an opening 38 between the concave flange 24 and the release lever 27. In order to resume grinding operation,

the concave 14 is manually swung about the hinge 16 so that its flange 24 will ride up on the inclined surface 31 of the lever 27. Inasmuch as the concave 14 has a fixed arcuate movement, it will be apparent that the release lever 27 must yield downwardly against the action of the spring 37. Immediately upon the flange 24 riding over the apex 32 of the lever 27, the spring 37 forces the lever 27 upwardly so that the flange 24 rides down the incline 30 and thereupon locks the concave in the position shown in Figure 2.

The spiral fluting 13 of the cylinder 12 performs two functions—first, that of preliminarily breaking up material to be ground and, second, that of feeding the grain longitudinally of the cylinder 12 to grinding plates 39 and 40. The plate 37 is permanently fixed to the housing 10 of the grinding mill, and the plate 40 rotates with the cylinder 12. Material to be ground is extruded between the plates 39 and 40 and then carried by thrower blades 41 to some depository. The means for driving the cylinder 12 and plate 40 may be one of several devices such as an electric motor or from the power take-off of a tractor, whichever is available. A lever 42 is provided on the outside of the feed grinder and permits adjustment of the plates 39 and 40 with respect to each other.

An opening 43 is provided in one of the side walls 10 of the feed grinder to enable an operator to insert his arm and pull down on the lever 27

5 and hence manually release the concave 14. A plate 44 hinged as at 45 or otherwise fastened is adapted to cover the opening 43. Such manual releasing may be necessary in cleaning out the feed grinder or for any other purpose which is deemed advisable.

10 It will be apparent that herein is provided a novel concave for feed grinders having a resilient locking means which permits automatic releasing of the concave as well as automatic relocking of the concave upon giving the concave a manual swing.

15 The intention is to limit the invention only within the scope of the appended claim.

What is claimed is:

20 In a material treating machine comprising a housing, a rotatable cylinder within said housing, a concave partially surrounding said cylinder, said concave being hinged at one side of said cylinder and fastened by means of a yieldable latch at the other side of said cylinder; said yieldable latch having means for automatically releasing the concave upon the attainment of a predetermined pressure between said cylinder and concave, and further means for manually releasing said concave, said latch comprising a hinged lever having an inclined portion slidably engaging a beveled lug on the concave, a spring adapted to normally hold said lever in engagement with said beveled lug.

25 JOHN R. HALL.
